UNITED STATES PATENT OFFICE.

SAMUEL HOAR, OF VIRGINIA, MINNESOTA.

TUNNELING-MACHINE.

1,206,437.

Specification of Letters Patent. Patented Nov. 28, 1916.

Application filed March 9, 1916. Serial No. 83,055.

To all whom it may concern:

Be it known that I, SAMUEL HOAR, a citizen of the United States, residing at Virginia, in the county of St. Louis and State of Minnesota, have invented certain new and useful Improvements in Tunneling Machines, of which the following is a specification, reference being had therein to the accompanying drawing.

19 This invention consists of certain improvements in tunneling machines and relates particularly to such machines adapted to ore mining and wherein the ore or refuse in a tunnel is shoveled into tram cars for removal therefrom.

The object is to provide a practical, cheap and efficient machine of this character.

Other objects and advantages will appear in the further description of the device.

20 In the accompanying drawings forming part of this application and in which like reference characters represent like parts: Figure 1 is a side elevation of the improved tunneling machine. Fig. 2 is a top plan view of same. Fig. 3 is a rear end elevation illustrating the shovel as operating at right angles to the position shown in Fig. 1. Fig. 4 is a cross sectional view of the chassis elevating device. Fig. 5 is a fragmental cross sectional view of the rear leg supporting device, and, Fig. 6 is a fragmental cross sectional view partly in perspective of the reciprocal carriage connection with the chassis.

30 The chassis of the machine is preferably of fabricated metal construction, comprising the two inclined elevated members 1-1 and end member 2, they being firmly united and forming three sides of a rectangular support for the shovel and its operating mechanism. The front end of the above described frame is supported upon the end frame 3, rigidly fixed thereto, and mounted upon an axle 4, carrying wheels 5-5, and which are designed to traverse the tram track as usually found in tunnels of this character. The rear end of the main frame is supported upon two legs 6-6, they being preferably of channel iron and rigidly braced to the main frame by suitable brackets 7.

Within the lowermost end of each leg 6 is securely fixed by means of bolts 8-8 a metal bearing block 9 having formed in the lowermost end thereof an inverted U-shaped bearing 10 which is designed to rest upon

the extreme end of the removable axle 11 which carries wheels 12-12, designed to traverse the tram track simultaneously with the forward wheels 5-5. Above the bearing 10 and through both the block 9 and the body of the channel 6 is formed a hole 13 in which is securely held by the nut 14, the journal pin 15, upon which is revolvably mounted the auxiliary supporting wheel 16, there being one of such upon each leg 6. The wheels 16-16 are preferably formed with sprockets or carks 17 around the circumferential faces thereof, to prevent slipping. These wheels remain idle and are above a level with the top of the tram rails, when the legs 6 are supported upon the axle 11, and the machine prepared to traverse the tram track, but when it is desired to station the machine prior to operating the shovel, the rear of the chassis is elevated sufficiently to remove the axle 11 with its wheels and by blocking up under the wheels 16-16 or allowing them to rest upon the ground, as preferred, the rear end of the chassis is supported upon said auxiliary wheels. By this adjustment it is evident that a tram car may be run in upon its track beneath the machine for loading purposes. As a means for raising and lowering the rear end of the chassis for the adjustment previously described, I provide within the end channel 2 a screw threaded block 18 through which vertically extends a similarly screw threaded rod 19 which has pivotally fixed upon the lowermost end thereof, a head member 20 and intermediate said head member and the under side of the channel 2 is fixed to the rod 19 the hand wheel 21 and by which the jack rod 19 is revolved. Thus when a support such as a bar or post, indicated by the dotted lines 22, is set up under the jack head 20 and the hand wheel revolved in a manner to withdraw the jack rod 19 from its bearing, it will cause the end of the chassis to be lifted, and such lifting when properly continued will free the legs 6-6 from engagement with their supporting axle 11, as previously stated. Then the machine may be lowered to rest upon its auxiliary wheels 16-16.

While I have shown the support for the jack as being a post or rod, it is evident that a tram car such as illustrated at 23 might be run up underneath the jack and by suitable blocking being placed thereupon, the end of the chassis thus elevated. In fact, if the

end of the chassis is allowed to remain thus jacked up upon a tram car, the machine may be transported from place to place thereupon without the use of the axle 11 and its wheels, and it is possible that this may be a preferable support for the rear end of the chassis while traveling upon the tram track.

24 represents the platform of the reciprocating carriage, mounted upon four rollers 26 and which have their tractive bearing within the members 1-1, as clearly illustrated in Fig. 6 of the drawings. The members 1-1 are preferably formed of channel iron and the frame 25 of the carriage of angle iron, the object being simplicity of construction.

20 The members 1-1 are shown as being inclined downwardly toward the front of the chassis, one object of which is to cause the reciprocating carriage to normally remain by gravity at the forward end of the chassis and thus require no power for such purpose. Upon the rear end of the chassis and 25 securely fixed thereto is a platform 27, upon which is mounted a suitable winding drum 28, having a rope connection 29 to the rear end of the platform 24 of the reciprocating carriage and whereby the carriage is operated toward the rear end of the machine. However it is understood that the line 29 might be an endless line running over a 30 sheave block at the forward end of the machine and made to operate the carriage in 35 both directions, if preferred.

I have illustrated the drum 28 as being operated by an electric motor 30, but it is evident that other forms of motor power might be utilized upon the entire machine, without departing from the spirit of the invention. Upon the platform 24 is pivotally mounted at 31 the shovel supporting platform 32, it having hinged upon the forward end thereof the shovel cylinder 33 which 40 carries the reciprocal shovel 34. Upon the opposite end of the platform 32 is mounted an electrically operated winding drum 35, similar to the drum 28, and by which the shovel cylinder is oscillated, through the medium of a suitable line connection 36 between the upper end of the cylinder and the drum 35. A cross arm 37 is rigidly fixed to the platform 32 transverse the pivotal center 31 thereof and having a handle 38 at each end whereby the platform 32 with its entire shovel mechanism may be manually trained or positioned upon its pivot 31 for guidance of the shovel when working.

60 It is to be understood that the machine as illustrated is for use within a tunnel approximately eight feet square and many parts of the mechanism are readily adjustable by hand. Vertically extending stops 39 are fixed to the sides of the members 1 and designed to contact that portion of the

ends of the cross arm 37 projecting beyond the edges of the platform 24 when the carriage is drawn to its rearmost position. Thus regardless of the angle of the shovel platform 32 in relation to the carriage platform 24, the former will be automatically drawn into alignment with the latter and at the conclusion of the rearmost travel of the carriage, the shovel will always be in direct alignment with the center of the chassis and directly over the tram car 23 to discharge therein.

Any form of controlling means such as a rheostat or switch may be located upon the sides of the machine, as at 40, where the power which operates the various parts of the mechanism may be controlled. The form of shovel and accompanying cylinder illustrated in the drawings are well known in the art and do not constitute part of my present invention, as it is evident various forms of such may be employed without departing from the spirit of the invention.

In ordinary operation the complete machine is transported upon the tram track, 90 its rear end being supported either upon a tram car or upon its removably adjustable truck axle 11, and its accompanying wheels, as above described, to the place of operation. The rear end is then elevated by the jack screw 19, the auxiliary supporting wheels 16-16, then blocked up and the previously utilized supporting means removed, from thereunder. The wheels 5-5 and 16-16 are then suitably blocked against revolution, 95 a tram car run beneath the chassis to be loaded, the line 29 slackened off, which will permit the carriage 25 to run by gravity to the forward end of the machine, the line 36 then slackened off, and the platform 32 trained to the desired position of the shovel 34, which may be adjusted within its cylinder 33 to any desired position, and in a manner common to the art, when it is ready for elevation. Then the drum 35 is put into 100 action which will cause the line 36 to draw the cylinder 33 down parallel with the platform 32, thus raising the shovel against the material to be excavated and filling same. The drum 28 is then set in motion causing draft upon the line 29, which will draw the carriage 25 toward the rear of the machine to its destination, when the shovel 34 will then be positioned directly over the tram car 23 and its load automatically dumped 105 therein, said automatic dumping being accomplished in any desired manner and which is common in the art.

Having thus described my invention what I claim as new and desire to secure by Letters Patent, is:

1. In a tunneling machine of the character described, the combination with a chassis having a reciprocal carriage therein carrying a pivoted shovel thereupon, of support.

ing wheels permanently mounted within the forward end of the chassis and designed to traverse a tram track, similar wheels and of a like gage supporting the rear end of the chassis but removably mounted therein, a third pair of wheels of considerably wider gage than that of the tram track fixed to the rear end of the chassis and designed to traverse a temporary track and means for vertically adjusting the rear end of the chassis for mounting it upon the temporary track whereby tram cars may be run in under the chassis and loaded by the shovel through the top thereof.

15 2. The combination with a tunneling machine chassis of permanently mounted tram track wheels in the forward end thereof, wheels of the same gage as the first mentioned wheels removably mounted in the rear end, a third pair of wheels of considerably greater gage than the other mentioned wheels mounted in the rear end of the chassis and designed to engage a temporary track and means for vertically adjusting the rear end of the chassis, to rest upon said wider gaged wheels whereby tram cars may be run upon the tram track beneath the chassis for loading purposes.

30 3. The combination with a tunneling machine, having a chassis mounted upon wheels and designed to traverse a tram track, of wheels permanently mounted in the front of the chassis and designed to traverse the track, a second pair of wheels of the same gage as the track but removably mounted within the rear of the chassis, a third pair of wheels of considerably wider gage than the track for support of the rear end of the chassis independent of the tram track when the second pair of wheels are removed and means for vertically adjusting the rear end

of the chassis, for removal of the second pair of wheels, to admit of tram cars being run under the chassis for loading purposes.

4. A machine of the character described, comprising a frame having permanent tram track engaging wheels at its forward end, removable similar wheels at its opposite end, a pair of auxiliary wheels for supporting the rear end of the frame from either side of the tram track, when the removable wheels are removed and means for adjusting the rear end of the frame whereby it may be supported upon said auxiliary wheels and tram cars run in under the frame for loading purposes.

5. An inclined tunneling machine chassis of the character described, having a pair of permanently fixed tram track wheels in the forward end, a pair of removable similar wheels in the rear end, and a pair of auxiliary wheels adjacent the removable wheels for supporting the rear end of the chassis when spanning the track to admit of tram cars passing thereunder for loading purposes.

6. The combination with a tunneling machine chassis of the character described, having an inclined upper shovel supporting deck, of means for portably supporting the entire chassis upon a tram track and means for portably supporting one end independent of the track whereby tram cars may be passed in under the end thus supported to be loaded by the shovel upon the inclined deck when desired.

In testimony whereof I hereunto affix my signature in the presence of two witnesses.

SAMUEL HOAR.
